UNITED STATES PATENT OFFICE.

HENRY VADE BONCOEUR, OF KANKAKEE, ILLINOIS.

DESIGN FOR A FLOOR LAMP.

Application filed January 21, 1925. Serial No. 12,103. Term of patent 3½ years.

To all whom it may concern:

Be it known that I, HENRY V. BONCOEUR, a citizen of the United States, residing at Kankakee, in the county of Kankakee and State of Illinois, have invented a new, original, and ornamental Design for Floor Lamps, of which the following is a specification, reference being had to the accompanying drawings, forming part thereof.

The figure is a side view of a floor lamp showing my new design.
claim:

The ornamental design for a floor lamp, as shown.

HENRY VADE BONCOEUR.
